(57) **CLAIM**

The ornamental design for a pneumatic tire, as shown and described.

DESCRIPTION

FIG. 1 is a front elevational view of a pneumatic tire showing my new design, it being understood that the tire tread pattern repeats circumferentially throughout the outer circumference.

FIG. 2 is a perspective view of the left-hand side of the pneumatic tire shown in FIG. 1, wherein the outermost solid line on the tire shoulder represents the boundary of the claim; the sidewall and broken line showing of the inner bead form no part of the claim.

FIG. 3 is a side elevational view of the left-hand side of the pneumatic tire shown in FIG. 1, wherein the outermost solid line on the tire shoulder represents the boundary of the claim; the sidewall and broken line showing of the inner bead form no part of the claim; and,

FIG. 4 is a side elevational view of the right-hand side of the pneumatic tire shown in FIG. 1, wherein the outermost solid line on the tire shoulder represents the boundary of the claim; the sidewall and broken line showing of the inner bead form no part of the claim.
